UNITED STATES PATENT OFFICE.

CARL P. SEYLER AND PERRY H. AUXER, OF CLEVELAND, OHIO.

CABLE-HANGING HOOK.

SPECIFICATION forming part of Letters Patent No. 694,677, dated March 4, 1902.

Application filed November 4, 1901. Serial No. 81,027. (No model.)

To all whom it may concern.

Be it known that we, CARL P. SEYLER and PERRY H. AUXER, citizens of the United States, residing at Cleveland, in the county 5 of Cuyahoga and State of Ohio, have invented a certain new and useful Improvement in Cable-Hanging Hooks, of which the following is a full, clear, and exact description, reference being had to the accompanying drawings.

This invention relates to a device for supporting a cable—for example, for the hanging of an electric cable from an overhead wire extending parallel with it.

15 The object of the invention is to provide the hanging device in a form which shall be very simple and cheap in construction, very easily applied, and very efficient and durable in operation.

20 To this end it consists, broadly, of a looped wire hook and a flat band adapted to pass through the loop and have its ends held by the plies thereof. The more particular embodiment of the invention herein shown and 25 described is also included in our invention.

In the drawings, Figure 1 is a perspective view as used of the best embodiment of our invention at present known to us. Fig. 2 is a side elevation of the same. Fig. 3 is a perspective view of the hook portion alone.

30 Referring to the parts by letters, A represents the hook proper, and B the band. The hook is made of wire bent intermediately to form the loop a , thus providing at least one horizontal upper ply and two substantially parallel lower plies a' a'' . Leading upward from one end of the ply a' and from the opposite end of the ply a'' are the legs a^3 a^4 , which at their upper ends are turned over to 35 make the hooks a^5 a^6 . The lower ply a^2 is bent outward and back on itself to form the U -shaped integral stud or lug a^6 . As will be seen from Fig. 2, when the legs of the hook a^3 a^4 are substantially vertical the lug a^6 projects diagonally downward.

40 The band B is a flat piece of metal—zinc, for example—and has one end b lapping over the ply a' of the hook. After passing over this ply the end may be riveted to the rest of 45 the band or it may be simply held thereto by being clamped by the spring-pressure of the plies a' a'' , between which it passes and which

may be sprung apart to receive it. This may be very conveniently done, as the device is supplied for use with the band secured at one 55 end.

In use the free end b' of the band B is passed around the cable C and tucked through the loop a , and an opening b^2 in the band is hooked onto the stud a^6 . There are as many 60 of these openings b^2 as desired, according to the use to which the band is to be put. When thus hooked on, the weight of the cable tends to draw the band more tightly onto the stud a^6 , and the stud extending diagonally downward, as shown, securely holds the band in place.

It will be seen that the construction is extremely simple, cannot get out of order, and requires no particular experience or dexterity 70 for its application and when once applied will securely hold the cable until released, which latter may be accomplished with equal ease by drawing the free end b' of the band diagonally downward and forward of the stud a^6 and then letting it pass back through the loop.

Having described our invention, we claim—

1. A cable-hanging device consisting of a looped wire hook combined with a flat band 80 having its ends held by the plies of the loop, substantially as described.

2. A cable-hanging hook consisting of a looped hook and a flat band having one end passing around one ply of the loop and the 85 other passing through the loop and held to it, substantially as described.

3. A cable-hanging device consisting of a looped hook with a stud projecting from one ply of the loop, combined with a band secured 90 at one end to another ply of the loop and having a hole adapted to hook over said stud, substantially as described.

4. A cable-hanging device consisting of a wire hook intermediately bent to form an integral projecting U -shaped stud, combined with a flat band secured at one end to the hook and having its other end perforated whereby it may hook over said stud, substantially as described.

5. A cable-hanging device comprising a wire hook having an intermediate loop and having one ply of said loop bent forward in a U shape to form a projecting stud, combined with a

flat band having one end passing around another ply of the loop and having its free end perforated to hook over the stud, substantially as described.

5 6. A cable-hanging device having a wire hook with vertical legs, a horizontal loop, and a diagonally downwardly projecting stud, combined with a flat band secured at one end to one of the plies of said loop and having its 10 other end perforated to hook over the stud, substantially as described.

7. In a cable-hanging device, a wire hook having substantially vertical legs bent over at their upper ends to form hooks and at their 15 lower ends bent horizontally toward each other to form a connecting-loop, one lower ply of the loop being bent forward and diagonally downward to form a projecting stud, in combination with a flat band secured to 20 an other lower ply of said loop and having its free end perforated, substantially as described.

8. A wire hook for a cable-hanging device having two vertical legs a^3 a^4 bent over into

hooks a^5 a^6 at their upper ends and connected 25 at their lower ends by a horizontal loop having two lower plies a^7 a^8 , the lower ply a^8 being intermediately bent outward and backward to form an integral U-shaped projecting stud a^9 , substantially as described. 30

9. A cable-hanging device comprising a wire hook and a flat band secured thereto, the hook being looped intermediately and the band having one end passing around one of the plies of the loop and clamped by being 35 squeezed between two adjacent plies of the loop, and means for securing the other end of the loop, substantially as described.

In testimony whereof we hereunto affix our signatures in the presence of witnesses.

CARL P. SEYLER.
PERRY H. AUXER.

Witnesses as to Carl P. Seyler:

ALBERT H. BATES,
ALBERT W. MAYERS.

Witnesses as to Perry H. Auxer:
